X6687 *Orice Reed.*

Letters Patent. August 31st 1853.

The schedule referred to in these Letters Patent, and making part of the same, containing a description in the words of the said Orice Reed himself of his improvement in the Pump.

The following is a description of the Pump used for pumping water, &c the improvements claimed thereon, &c.

The principal parts consist of a perpendicular tube in the form of the upper part of a pump, with its flange, bottom plate, valve, movable top, rod, lever, screws & bolt. This pump is made of cast iron, wrought iron or other metal. The body of this pump now used, is about two feet in length; the caliber is from two to three inches according to the quantity of water required; at the bottom of the caliber is a projection or flange extending about eight inches in diameter; under the flange is a plate about twelve inches in diameter, of suitable thickness for the strength required. Through the centre of said plate is a hole about an inch and a quarter to an inch and a half diameter, on the upper side of the hole is an elevation about an eighth of an inch in height, and a little more than an eighth of an inch in width, in a circular form corresponding with the hole, on which the lower valve sits. Near the circumference of the plate are a sufficient number of holes for wood screws or bolts, that said plate may be attached to any board or plank in whatever place said pump may be used. The thickness of the pump from the caliber to the surface is a little more than a quarter of an inch. The flange of the perpendicular tube is put together by screws centrally over the lower valve, & is made tight by placing a circular piece of thin leather, or any other suitable material between the bottom plate and flange. The lower valve is attached to the lower plate by copper screws.

or valve, so that the body of the pump may be taken off from
at the lower valve without disturbing the lower plate or pipe.
The plate is connected with the pipe by means of a collar with a
suitable hole through it to receive the end of the pipe. The upper
end of said pipe being turned outwardly & bent over in the
form of a flange, & is made tight by being firmly secured to the
bottom plate, having also a circular piece of leather placed on
the top of said flange in the same manner as between the plates
of the flange on the bottom of the pump. The movable box is about three
inches long and turned to the size of the caliper of the body
of the pump. A groove is turned in the middle part of said box for
the purpose of winding rope, yarn or leather, so that said box may
be kept tight. On the upper side of said box a valve is placed &
fastened in the same manner as the lower valve on the bottom
plate. A staple is attached to said box with a joint about
two or three inches above said valve, and is connected to the
lever by a pin; this joint is to prevent the friction otherwise
occurred by the circular motion of said lever. The lever is at-
tached to said pump in the common form. A brass thumb screw is in-
sulated in the lower part of said pump, a little above the flange, by
being turned, the inner end passes the valve so as to let the water off
to prevent it from frost. The cast iron tube or pipe, is made from two to five
feet in length, as may be found most convenient, with a suitable caliper,
being larger at one end than the other, so that they may be put together
similar to the funnel of a stove. These tubes are made fast together by
two loops or ears opposite each other. The loop on the large end of the
pipe is even with the end, and those on the small end of the pipe
are about one inch from the end, which will admit of entering one
inch. These loops are about three quarters of an inch in width, & of
sufficient thickness for strength, and when put together are secured by a
link in the form of a chain and made tight by packing. The loops
and links may be multiplied as may be required.

the improvements claimed, and for some have been used without
the knowledge of your petitioner, and) the bottom plate in a horizontal position
with a valve attached with one playing upon said elevation; and
the manner of connecting it with the plate as set forth in the above spe-
cification.

The joint connecting the effluent with the rod, by the screw for
letting off water in the manner above described, by which the pump
is made much easier, at a less expense, and the manner of putting
together the tube, & fastening the same, which is a substitute for the
lead pipe.

Witness,

Wilson Young
Frank Reed.
